CHILD'S HAND PROPELLED VEHICLE

Leonard R. Stillson, Jr., 6838 Silverthorne Circle,
Sacramento, Calif.

Filed Sept. 29, 1967, Ser. No. 8,798

Term of patent 14 years

(Cl. D34—15)

FIG. 1.

FIG. 2.

FIG. 3.

FIG. 2 is a top plan view thereof; and

FIG. 3 is a front elevational view thereof.

I claim:

The ornamental design for a child's hand propelled vehicle, substantially as shown.
